LOOM FOR WEAVING TUFTED PILE FABRICS

Isaac Bradley Bassindale, Oldham, England, assignor to Platt Brothers and Company Limited, Oldham, England

Application September 13, 1950, Serial No. 184,552
In Great Britain September 15, 1949

6 Claims. (Cl. 139—336)

1

This invention of improvements relating to looms for weaving tufted pile fabrics, refers to spool Axminster carpet looms and in particular to the transferring mechanism for disengaging and removing tube frames each carrying a spool of tuft yarn from the carrying chains of a loom and transferring them to the place where tuft yarns are inserted between warp threads, and restoring the tube frames to the carrier chains.

In the operation of said transferring mechanism the tuft yarns guided in guide tubes on the tube frames are inserted between the warp threads and subsequently the tufts are severed from the yarn in the tube frame and the tube frame is restored to the carrier chains.

It sometimes happens that a tuft is not properly severed by the knives and as the tube frame is raised to the carrier chains the unsevered length of tuft yarn is dragged upwards and, being anchored to fabric at the fell of the said fabric, becomes tangled and may cause the tube frame to be pulled out of the carrier chains to fall on to the loom and possibly cause damage. Or the tube frame may be carried round by the carrier chains with the tuft yarn unsevered and when the next tube frame is taken from the carrier chains and moved to insert tuft yarn between the warp threads the knives moving forward endeavour to cut the double tuft yarn.

The present invention has for its object the provision of electrically operated stop-motion mechanism, whereby the loom is automatically and instantaneously stopped in the event of tuft yarn not being properly severed by the knives and an uncut length of tuft yarn being carried by the tube frame in its return journey to the carrier chains, the stop-motion being adapted to be brought into operation on failure of the knives to sever the tuft yarn at any point along the width of the fabric.

The invention consists in electrically operated stop motion mechanism for a spool Axminster carpet loom of the type referred to adapted to be brought into operation on failure of the knives to sever the tuft yarn at any point along the width of the fabric by means including a cradle pivotally mounted on an overhead shaft in the loom and having a light cross-bar extending the full width of the fabric and located above and slightly to the front of the fell of the fabric, said cradle being in operative association through a lever system with a cam set in timed relation to the main cams of the loom whereby the cradle may be swung backwards and forwards out of the path of movement of the tube carrier, an

2

electrical contact terminal secured to a bracket on the loom frame adjacent to one of the side pivots of the said cradle insulated from the loom frame and forming one terminal in the low voltage circuit of the electrical stop motion, a bar pivoted to the loom frame adjacent to said contact terminal and forming the other terminal of the low voltage circuit, and a sequence switch intercalated in the low voltage electrical circuit associated with the motor starter and means for operating said switch in timed sequence.

An illustrative embodiment of the invention will now be described with the aid of the accompanying drawings in which only so much of a spool Axminster carpet loom is shown as is necessary for a clear understanding of the invention.

In the drawings, Fig. 1 is a fragmentary front view, broken to shorten the figure, showing the invention applied to a spool Axminster carpet loom; Fig. 2 is a sectional side elevation of the parts shown at the center and right in Fig. 1, looking toward the right and drawn to a reduced scale, Fig. 2 also showing an auxiliary cam later referred to; Fig. 3 is a diagram of the electric circuit.

The same reference characters indicate corresponding parts in the several figures of the drawings.

Referring to Figs. 1 and 2, 10 indicates the frame of the loom; 11, 12 indicates a pair of brackets secured to the loom frame in which is revolvably mounted a shaft 13. Suspended from and secured to the shaft 13 is a cradle 14 comprised of pendant side arms 15, 16 joined at their lower extremities by a light cross-bar 17 extending the full width of the fabric and normally located above the fell of the fabric being woven and slightly on that side of the fell nearest the front of the loom. One arm 16 of the cradle 14 is provided at the rear with a projection 18 furnished at its extremity with a bowl or roller 19.

In the rear of the cradle 14 there is located a bell-crank lever 20 pivoted at 21 in a bracket 22 secured to the loom frame 10.

The free end of the longer arm 23 of the bell-crank lever 20 projects below the roller 19. The shorter arm 24 of the bell-crank lever 20 is furnished adjacent to its extremity with a screw-threaded bolt 25. Located on the loom frame 10 adjacent to said screw bolt 25 is a sequence switch 26 having a contact plunger 27 adapted for contact by the terminal screw bolt 25. The sequence switch may be constructed simi-

lar to the sequence switch disclosed in pending application Ser. No. 150,272, filed March 17, 1950, in which the sequence switch is disclosed as comprising a plunger corresponding to the plunger 27 which is adapted to bridge a pair of contacts arranged in the switch housing. The contacts of this sequence switch 26 are arranged in the low voltage circuit in the manner shown in Fig. 3 of the drawings.

The bell-crank lever 20 is in operative association by means of a rod 28 connected to the arm 23 of the bell-crank lever 28 with an auxiliary cam, set in timed relation with the main cams of the loom. The rod 28 is connected at its lower end to one end of a lever 28^a pivotally connected at 28^b to a bracket 28^c carried on the loom frame, the lever 28^a being furnished at approximately mid-position with a bowl 28^d tracking the auxiliary cam 28^e. The rod 28 is in two parts adjustably connected together by a turn-buckle 29.

Located adjacent to one of the pivots of the cradle 14 between the arm 16 of the cradle and the adjacent bracket 12 is an electrical contact terminal 30 which is secured to, but insulated from, the frame 10 of the loom by an insulation piece 31.

The terminal 30 forms one terminal in the low voltage electrical circuit, the other terminal of which is provided by a screw terminal 32 adjustably mounted in a bracket 33 hinged at 34 to the frame 10.

The bracket 33 is furnished adjacent to its free extremity with a screw-threaded bolt 35, the lower end of which projects into the path of movement of an arm 36 fast on the shaft 13 adjacent to the arm 16 of the cradle 14.

As seen in Fig. 2, 37 is a tube frame which is operated in known manner by a tube carrier, not shown.

In the normal working of the loom the two terminals 30, 32 are maintained in the closed position during a portion of the loom cycle, but no current flows through the low voltage circuit until the sequence switch 26 therein and associated with the electric circuit of the starter of the driving motor is moved into the "on" position by cam action.

When the tube carrier carrying the tube frame 37 moves into operative position to insert tuft yarn between the warp threads the cradle 14 is swung backwards about its pivot by the lever arm 23, which, under the upward movement of the rod 28 actuated by the aforesaid auxiliary cam, presses against the roller 19 in the extension 18 of the cradle arm 16. This backward movement of the cradle 14 displaces the cross-bar 17 out of the path of movement of the tube carrier, and the operation of the loom continues.

When the tube carrier is lifted and restored to the carrier chains, the cradle 14 is again swung forward to its initial position, the extension arm 36 adjacent to the cradle arm 16 presses against the screw 35 to rock the bracket 33 about its hinge 34 and thereby break contact between the terminals 30 and 32 so opening the low voltage circuit, and the loom continues to work.

Should the knives fail to sever a tuft yarn at any point along the width of the fabric being woven, the tube frame carrier, in being restored to the carrier chains, takes with it the uncut length of tuft yarn and, when the cradle 14 is swung forward as aforesaid, the cross-bar 17 meets against the taut uncut length of tuft yarn as indicated at Y, Fig. 2, and the forward traverse

of the cradle 14 is arrested as shown in Fig. 2. The terminals 30, 32 of the low voltage circuit therefore remain in contact.

When, now, the switch 26 in the low voltage circuit associated with the starter circuit is put into the "on" position by action of the before-mentioned auxiliary cam in effecting the downward movement of the arm 23, the inward movement of the arm 24 and the actuation of the plunger 27 to close the sequence switch 26, electrical current flows through the low voltage circuit.

The completion of said circuit serves to energise a relay, which in turn operates the starter to break the electric circuit of the driving motor and bring about stoppage of said motor, whereupon the loom is brought to a standstill before any damage is sustained.

The sequence of operations of the electric stop motion will be described with reference to the diagram shown in Fig. 3, in which B indicates a transformer for low (safe) voltage; C indicates a trip relay with one normally closed contact indicated at C¹; D indicates a relay with two normally open contacts, D¹, D²; E indicates a trip contact switch on the loom, the contacts 30 and 32; F indicates a change-over push unit actuated by the loom starting handle, having four terminals F¹, F², F³ and F⁴; G indicates a re-set button on the loom; H indicates a signal lamp; J indicates a sequence switch, the switch 26.

The operation is as follows:

With the loom running normally, all the contacts and relays are as shown in the diagram, but when the forward movement of the cradle 14 is arrested by an uncut length of tuft yarn the terminals 30, 32, corresponding to the switch E, remain in contact, so maintaining the switch E of the diagram closed, the electric circuit is not completed until the sequence switch J is closed (corresponding to sequence switch 26), thus energising the relay coil D and closing contacts D¹, D², contact D¹ providing an alternative path for electric current through the relay coil D, making the relay coil D self-retaining and now independent of the contact at E. The contact D² being closed provides a circuit through the contacts F¹, F² and relay coil C, thus breaking contact C¹ which causes the circuit to the electric motor to be opened automatically when the supply voltage fails, whereby to trip the starting handle and stop the loom.

The starting handle, which is spring-loaded, thus returns to the "off" position and in so doing releases the clutch between the electromotor and the loom and applies a mechanical brake, at the same time also releasing the change-over push unit F, breaking contact between F¹ and F² and bridging F³ and F⁴.

The relay coil is now de-energised and C¹ returns to normal closed position. An alternative circuit then flows through contacts F³, F⁴, lamp H and contact D¹, thus indicating the cause of the stoppage.

The driving motor can be switched on if required and the loom "inched" at the operator's will, but, if the starting handle is moved to full "on" position before removal of the cause of stoppage, the stop motion will again act.

Having rectified the cause of the stoppage, the operator can then press the re-set button G, and the loom is again ready for running.

The means for moving the starting handle quickly from "on" position to "off" position are described in the specification filed with co-pend-

ing application for Letters Patent No. 150,272, March 17, 1950.

Instead of the sequence switch 26 operated by the cam operated lever 20 a cam operated sequence switch as described in the aforementioned specification may be employed.

The provision of an electrically operated stop-motion as described ensures that the loom is stopped automatically if the forward traverse of the cradle is arrested by an uncut tuft yarn.

The cradle is of very light construction and even a single uncut length of tuft yarn at any point in the width of the fabric will hold the cradle back and prevent its forward movement being completed.

What I claim is:

1. In an electrically operated stop motion mechanism for spool Axminster tufted pile fabric looms of the type including transferring mechanism for disengaging and removing tube frames each carrying a spool of tuft yarn from carrying chains of the loom and transferring them to the place where tuft yarns are inserted between warp threads of the tufted pile fabric being woven and are cut by the loom knives and restoring the tube frames to the carrier chains, said electrically operated stop motion mechanism including an electrical circuit for automatically stopping the loom on failure of the knives of the loom to sever the tuft yarn at any point along the width of the fabric being woven by the loom, a loom frame, an overhead shaft pivotally mounted on the loom frame, a cradle carried on said pivotally mounted shaft including a cross bar extending the full width of the fabric being woven by the loom, said cross bar being normally located above and slightly to the front of the fell of the fabric, a lever system carried by the loom frame including a projecting arm which moves upwardly and downwardly in timed sequence during the loom cycle, said projecting arm being operatively associated with said cradle for swinging said cradle backwardly during the upward movement of said arm and for permitting said cradle to swing forwardly during the downward movement of said arm, a sequence switch in said circuit operatively associated with said lever system for actuation to closed position thereby upon downward movement of said arm, and a second switch in said circuit in series with said sequence switch whereby said circuit is closed and the loom stopped when said sequence switch and said second switch are both closed at the same time, said second switch being operatively associated with said cradle and arranged to be actuated to closed position when said cradle is swung backwardly by said arm of said lever system during its upward movement, said second switch being held in closed position by said cradle upon the failure of the knives of the loom to sever a tuft yarn which in turn is engaged by said bar and prevents said cradle from moving forward after being swung backwards by the upward movement of said arm of said lever system.

2. An electrically operated stop motion mechanism for spool Axminster looms as claimed in claim 1, in which said cradle comprises a pair of pendent side arms to the lower ends of which said cross bar is attached, and an arm projecting from the rear of one of said pendent side arms and having a roller mounted thereon operatively associated with and adapted to engage the upper surface of the projecting arm of the lever system.

3. An electrically operated stop motion mechanism as claimed in claim 2, in which said lever

system comprises a bellcrank lever pivotally mounted behind said cradle and in which said projecting arm of the lever system is an arm of said bellcrank lever, the other arm of said bellcrank lever being operatively associated with said sequence switch for effecting its operation.

4. An electrically operated stop motion mechanism for spool Axminster looms as claimed in claim 1, in which said second switch includes a contact mounted on the loom frame and insulated therefrom, a movable contact electrically connected to the loom frame and normally biased to closed position with respect to said fixed contact, and means operatively associated with said cradle for disengaging said movable contact from said fixed contact when the cross bar of said cradle is in its normal forward position and for permitting said movable contact to engage said fixed contact when said cradle is swung backwardly.

5. An electrically operated stop motion mechanism for spool Axminster looms as claimed in claim 1, in which said second switch comprises a fixed electrical contact terminal mounted in fixed position with respect to the loom frame and electrically insulated therefrom, a movable electrical contact terminal pivotally mounted with respect to the loom frame adjacent to said fixed contact terminal and adapted to normally engage said fixed contact terminal, and an arm operatively associated with said cradle and movable in sequence therewith for lifting said movable contact from the fixed contact when the cross bar of the cradle is in its normal forward position and to permit said movable contact to engage said fixed contact when the cradle is swung backwardly.

6. In an electrically operated stop motion mechanism for spool Axminster carpet looms of the type including a loom frame, carrying chains, tube frames each carrying a spool of tuft yarn, knives for cutting the tuft yarn, and transferring mechanism for disengaging and removing tube frames carrying a spool of tuft yarn from the carrying chains of the loom and transferring them to the place where tuft yarns are inserted between warp threads of the tufted pile fabric being woven by the loom and for restoring the tube frames to the carrier chains, said electrically operated stop motion mechanism including an electrical circuit for automatically stopping the loom on failure of the knives of the loom to sever the tuft yarn at any point along the width of the fabric being woven by the loom, a cradle pivotally mounted on the loom frame and including a cross bar extending the full width of the fabric being woven by the loom, said cross bar being normally located above and slightly to the front of the fell of the fabric, a lever system carried by the loom frame including a projecting arm which moves upwardly and downwardly in timed sequence during the loom cycle, said projecting arm being operatively associated with said cradle for swinging said cradle backwardly during the upward movement of said projecting arm and for permitting said cradle to swing forwardly during the downward movement of said projecting arm, a sequence switch in said electrical circuit operatively associated with said lever system for actuation thereby in timed sequence to closed position upon the downward movement of said projecting arm, and a second switch in said electrical circuit in series with said sequence switch whereby said circuit is closed and the loom stopped only when said sequence switch and said

70

second switch are both closed at the same time, said second switch being operatively associated with said cradle and arranged to be actuated to closed position when said cradle is swung backwardly by said projecting arm of said lever system during its upward movement, said second switch remaining in closed position upon the failure of the knives of the loom to sever a tuft of yarn which in turn is engaged by the bar of the cradle and prevents said cradle from moving forward after being swung backwards by the upward movement of said projecting arm of said lever system, said lever system in the subse-

quent downward movement of said projecting arm actuating said sequence switch to closed position thereby closing said electrical circuit and stopping the loom.

ISAAC BRADLEY BASSINDALE.
